UNITED STATES PATENT OFFICE.

ROBERT H. VAN SANT, OF CHICAGO, ILLINOIS, ASSIGNOR TO VAN ESS LABORATORIES, INC., OF CHICAGO, ILLINOIS, A CORPORATION OF DELAWARE.

SHAMPOOING-BOTTLE CAP.

Application filed September 20, 1923. Serial No. 663,854.

This invention relates to a massage device of that type especially designed for massaging the scalp and comprises a perforated rubbing element adapted for attachment to a bottle or vessel for allowing an ointment to percolate therethrough during the massaging operation.

Heretofore such rubbing or massaging elements have been moulded from rubber or the like in the form of a cap having internal threads whereby the cap could be screwed upon the neck of a bottle. It required complicated dies to mould such caps, besides the process was laborious and tedious and mitigated against large scale production.

It is an object of this invention to overcome the above noted objections by providing a massaging element in the form of a disk and attaching the same to the bottle by means of a removable metal ring or the like; such a massaging element merely requiring a simple die that can be quickly made, and that simplifies the moulding process so that production is greatly increased.

25 A further and important object is to compensate for any swelling action of the rubber disk massaging element, due to the action thereon of the ointment being dispensed, whereby distortion of said disk is minimized.

30 It is also an object of this invention to provide for the control of fluid through the massaging element as will later more fully appear.

35 It is a further object of this invention to provide such a massaging device which will provide a vacuum effect for absorbing or drawing impurities from the skin or scalp.

With these and other objects in view which will become more apparent in the 40 following description and disclosures, this invention comprises the novel structure and combinations hereinafter described and more particularly pointed out and defined in the appended claims.

45 In the accompanying drawings, which illustrate a preferred embodiment of this invention and in which similar reference numerals refer to similar features in the different views:

50 Figure 1 is an elevational view of an ointment bottle with my invention applied thereto.

Figure 2 is a top plan view of the massaging element.

Figure 3 is a bottom plan view of the 55 massaging element.

Figure 4 is an enlarged vertical section through the massaging element.

Figure 5 is an enlarged vertical sectional view through a modified form of massaging 60 element.

Figure 6 is an enlarged top plan view of the modified form of massaging element.

Figure 7 is a fragmentary sectional view of a further modified form of massaging 65 element.

Figure 8 is a detail sectional view illustrating the operative position of the expansion joint.

Referring to the drawings, which illustrate certain embodiments of this invention, there is shown an ointment bottle 1 having an external screw-threaded neck 2 upon which a ring or cylindrical member 3 is adapted to be screwed for confining the 70 massaging element 4 which is in the form of a rubber disk having an external diameter substantially equal to the internal diameter of the ring. The ring 3 which is preferably made of sheet metal, is provided with an 75 internal marginal flange 5 at its upper end which overlaps the circumferential margin of the rubber disk and clamps the same tightly upon the top of the bottle.

This massage element is provided with a 80 slightly raised central portion 6 from which a circular series of flexible rubbing teeth 7 project. Within the circular series of flexible rubbing teeth extend a plurality of perforated projections 8 of lesser height than 85 the teeth 7, for supplying the ointment from the bottle during the massaging operation when the bottle is tilted so as to be substantially upside down. It will be noted that the perforations 8, through the projections 90 8 are restricted at their inner ends and diverge outwardly. Normally these restricted 95 passages are substantially closed so that only a small quantity of ointment will seep therethrough. However, when these projections 100 come in contact with the scalp or skin and are flexed, the restricted passages will be more or less opened and this flexing will cause a greater flow of ointment. The circumferential margin of the massage disk 4 105 beyond the central raised portion is adapted to underlie the flange 5 of the ring as shown in Figure 4, so that an efficient seal is pro-

vided to prevent improper escape of the ointment during the massaging operation. Upon the lower surface of the disk there is an annular rib 9 which fits within the neck 5 of the bottle. This rib tends to strengthen the disk and adds a certain amount of rigidity thereto. Within the confines of the rib 9 there is a groove 9^a for expansion purposes. Certain kinds of ointment will cause 10 a swelling or expansion of rubber. In such a case, the rib 9 will be expanded outwardly against the inner surface of the bottle to assist in sealing the liquid therein, as shown in Figure 8. Said groove 9^a under such 15 swelling action opens, permitting an additional expansion to the rib 9.

In Figures 5 and 6 there is illustrated a slight modification of massage disk. It mainly differs from the one just described 20 in the substitution of a flexible or resilient circumferential flange 10 for the flexible rubbing teeth 7, whereby a form of vacuum cup is formed that tends to draw the impurities from the scalp and at the same time increases 25 the flow of ointment through the supply ducts in the projections or teeth 8. In Figure 7, this vacuum massage cup is shown as provided with perforated projections 8^a which terminate in vacuum cups at their 30 upper end whereby the flow of ointment therethrough may be accelerated.

In both forms of the massaging disk, the central portion is thicker than the more remote portions whereby the tendency to upward expansion of the disks is decreased or 35 overcome so that the flow of ointment through the apertures 8^b will not be affected.

It will readily be appreciated that the 40 massage disks are of simple construction and can be quickly moulded. The metal rings can also be stamped in mass production. In assembling, it is only necessary to insert the massage disks within the rings. They are intended to fit sufficiently tight therein so that they will be frictionally retained.

The massage ointment is adapted to be sold in bottles which are closed by a metal cap. A massage disk assembled in a metal

ring is intended to accompany each bottle. So it is only necessary to remove the metal 50 cap from the bottle and apply the metal ring with the contained massage disk.

I am aware that many changes may be made and numerous details of construction may be varied through a wide range without departing from the principles of this invention, and I therefore do not purpose limiting the patent granted hereon otherwise than necessitated by the prior art.

I claim as my invention:

1. The combination with an ointment container having an outlet, of a massaging device comprising a disk-shaped flexible rubber member positioned over said outlet, means for confining said disk over said outlet comprising a cylindrical member having a flange engaging the margin of said disk, a circular sealing rib upon the inner surface of said disk for preventing the escape of ointment between said disk and cylindrical 70 member, and a circular expansion groove disposed interiorly of said rib, whereby to allow for the outward expansion of said sealing rib under the swelling action of the rubber when exposed to the ointment being 75 dispensed.

2. The combination with an ointment container having an outlet, of a massaging device disposed over said outlet and embodying a flexible circumferential flange adapted to 80 operate as a vacuum cup, and projections disposed within said flange having ointment supply ducts therethrough.

3. The combination with an ointment container having an outlet, of a massaging device disposed on said outlet and embodying a flexible circumferential flange adapted to operate as a vacuum cup, and flexible projections disposed within said flange having 85 ointment supply ducts therethrough and 90 formed at their discharge ends into individual vacuum cups.

In testimony whereof I have hereunto subscribed my name.

ROBERT H. VAN SANT.
